CIGARETTE PACKAGE

Edward F. Cornock, Springfield, Mass., assignor
to Package Machinery Company, Springfield,
Mass., a corporation of Massachusetts

Application February 3, 1940, Serial No. 317,093

6 Claims. (Cl. 229—51)

This invention relates to an improved package particularly intended for cigarettes and to an improved method by which the article may be made.

One customary manner of opening a cigarette package is to tear off a corner of the top, thereby exposing the ends only of a few cigarettes and keeping the package intact except for this small opening. It has recently become customary to place around this complete cigarette package an additional outer covering of one of the transparent cellulose derivatives. This type of material is notoriously difficult to tear, and in order to permit the described way of opening the package to be employed it has hitherto been necessary to remove the entire transparent wrapping, or in some instances to provide a tearing strip by which the whole top of the outer wrapper may be torn off.

In accordance with the present invention, a tearing strip is provided, so located that only the corner of the wrapper which is to be exposed will be torn off. Preferably, and as will be described below, the wrapper and the tearing strip are so arranged that the removal of the torn part does not tend to open up any of the overlapping and sealed portions of the wrapper and so that the remainder of the transparent wrapping will remain intact after the desired corner has been removed.

It is a further object of the invention to improve the method of assembling the tearing strip with the wrapper so that this assembly may be accomplished by automatic machinery without requiring any changes whatever in the method of wrapping.

Additional objects will appear from the following description and claims.

Referring to the drawing:

Fig. 1 is a perspective detail showing a blank with the improved tearing strip applied thereto and also indicating the initial assembly of an article with this wrapper;

Fig. 2 is a perspective view of the wrapped article;

Fig. 3 is a detail of the left hand end of the article as seen in Fig. 2;

Fig. 4 is a detail of a wrapper showing a modified form of tearing strip; and

Fig. 5 is a detail corresponding to Fig. 2 but employing the tearing strip of Fig. 4.

The article 10 may be a pack of cigarettes, in which case the cigarettes lie in the direction of the arrow 11. A blank 12 is employed in which to wrap the article, this being folded upon the article in such a manner as to produce side tucks

13 and overlapping side folds 14 and 15. This produces a tubular extension of the wrapper which is subsequently folded down with tucks 16 and overlapping flaps 17 and 18.

For the practice of my invention the end 19 of the article against which the wrapper first makes contact is chosen for the top of the finished article and it is the corner of this top which it is desired to remove by tearing. It will be observed that this top is unbroken by folds and that for this reason it is not accessible for tearing without the use of my invention.

A tearing strip indicated generically by 20 is secured adhesively to the wrapper 12 before the latter is folded around the article. This tearing strip is made in the form of a V with a broad rectangular base 21, this base being positioned across the top of the article with its upper edge, as viewed in Fig. 1, lying across the edge 22 of the article. The rhomboidal sides 23 of the V are caused to extend a short distance beyond the body of the blank as at 24. In order to facilitate the tearing of the wrapper a slit 25 is preferably formed in the wrapper at that side of the tearing strip which is to come uppermost and form the fold 14.

The blank with the tearing strip adhesively secured thereto is folded around the article in the manner described above. The portion 21 of the tearing strip lies across the corner of the top of the wrapper while the V-shaped edges 23 extend first as a diagonal band across the flat sides of the package and then overlap each other as triangular extensions underlying the folds 14 and 15. If the outermost triangular extension be grasped the cellulose wrapper will be torn; starting at the notch 25, extending completely around the sides and top of the article, and finally tearing the underlying fold 15 so that a patch is ex-

posed of a shape corresponding directly to that of the tearing strip, as shown in Figs. 2 and 3.

It may be that the outer triangular tab is somewhat hard to distinguish on account of the fact that one of these tabs lies directly over the other. It is generally desired to indicate by a different color of the tearing strip the location of the tab to be pulled and for that reason some confusion may result in the case as described above where the overlying tabs are of the same color. If this be so, the two triangular extensions can be offset by varying the angular relation of the two sides of the V-shaped tearing strip as shown in Fig. 4. In this case the bottom 30 is flanked by the two slanting sides 31 and 32, the former being indicated as lying at a steeper angle

than the other. This results in a shorter lateral extension 33 on the side 31 than the distance 34 on the other side. When the tearing strip so constructed is wrapped around the package as indicated in Fig. 5 the side portion 32 will extend somewhat further down the side of the package, making it perfectly clear where the tearing strip may be grasped.

What I claim is:

1. A package comprising an article, a wrapper encircling the article and presenting an unbroken surface across the top face and a pair of adjacent faces thereof and having overlapping side folds on a side adjacent said top and intermediate said faces, and a tearing strip underlying a portion of the top face of the wrapper, extending diagonally across said adjacent faces, and thence extending underneath each of said overlapping flaps whereby when the tearing strip is pulled the wrapper will be torn off from around one corner of the top and from the faces and side adjacent thereto, the ends of said tearing strip being positioned out of alignment with each other.

2. A package comprising an article, a wrapper encircling the article and presenting an unbroken surface across the top face and a pair of adjacent faces thereof, and having overlapping side folds on a side adjacent said top and adjacent faces, and a tearing strip underlying a portion of the top face of the wrapper, extending diagonally across said adjacent faces, and thence extending underneath each of said overlapping flaps whereby when the tearing strip is pulled the wrapper will be torn off from around one corner of the top and from the faces and the side adjacent thereto.

3. A cigarette package comprising a wrapped package of cigarettes, an outer wrapper extending around the package, and a tearing strip located between the package and the wrapper and defining a path extending across two adjacent sides forming an edge of the package and diagonally across the sides contiguous to the first two sides

and located at the opposite ends of the edge, one end of the strip extending between overlapping folds of the wrapper.

4. A cigarette package comprising a wrapped package of cigarettes, an outer wrapper extending around the package, and a tearing strip located between the package and the wrapper and defining a path extending across two adjacent sides forming an edge of the package and diagonally across the sides contiguous to the first two sides and located at the opposite ends of the edge, one end of the strip extending between overlapping folds of the wrapper, said tearing strip being adhesively secured to the inner surface of the wrapper.

5. A cigarette package comprising a wrapped package of cigarettes, an outer wrapper extending around the package with an unbroken surface across the top and a pair of adjacent faces, and a tearing member adhesively secured to the inner surface of the wrapper, said member having a rectangular portion secured to one end of that portion of the wrapper extending over the top of the package and a pair of rhomboidal portions extending diagonally across said adjacent faces and into overlapping relation on the article side adjacent thereto.

6. A cigarette package comprising a wrapped package of cigarettes, an outer wrapper extending around the package with an unbroken surface across the top and a pair of adjacent faces, and a tearing member adhesively secured to the inner surface of the wrapper, said member having a rectangular portion secured to one end of that portion of the wrapper extending over the top of the package and a pair of rhomboidal portions extending diagonally across said adjacent faces and into overlapping relation on the article side adjacent thereto with one corner of one of said rhomboidal portions exposed in offset relation to the other portion.

EDWARD F. CORNOCK.
